APPARATUS FOR DEVELOPING PHOTO-
GRAPHIC FILMS

Harold A. Windisch, Lansdowne, Pa.

Application October 9, 1935, Serial No. 44,259

9 Claims. (Cl. 95—90.5)

This invention relates to improvements in apparatus for developing photographic films. The invention has for its principal object the provision of novel apparatus in which the entire developing process, inclusive of the steps of immersing the film in the developing solution, the subsequent washing of the film to free it from the developer, and the fixing and final washing operations, may be conducted under full daylight conditions and without recourse to a dark room.

To this general end, another and specific object of the invention is to provide a light-proof tank equipped with novel means for unwinding the undeveloped film from the roll and for guiding the film into an adequately supported position within the tank in which all parts thereof are exposed for contact with the developing liquids, said means providing for exclusion from active contact with said liquids of the backing paper with which the film is conventionally provided, as well as any other foreign materials which might adversely affect the film.

A further object of the invention is to provide novel apparatus of the character set forth permitting inspection of the film at any time during the developing, fixing or washing operations.

Still another object of the invention is to provide apparatus of the stated character in which all working parts are removable to facilitate cleaning, and in which all surfaces exposed to the developing chemicals are available for cleaning and drying.

A further object of the invention is to provide in apparatus of the stated character novel means for locating the film in a fixed position in which it is maintained at all times during the developing process.

Still another object of the invention is to provide apparatus of the stated character which shall be adjustable and readily adaptable to different sizes of film, thereby making possible the use of a single tank or container for films of various sizes.

A still further object of the invention is to provide a developing tank provided with novel means for automatically regulating the depth of the liquids in the tank and for preventing the trapping of air in the tank when the liquids are admitted.

The invention further contemplates the provision of a portable device of the stated character of relatively inexpensive construction that may be built economically of any suitable acid-resisting material and which can be used under any light conditions and at any place where water is available.

The foregoing and further objects hereinafter appearing are attained by means of the novel devices illustrated in the attached drawings, wherein:

Figure 1 is a view in perspective of the assembled tank; 5

Fig. 2 is a plan view of the tank with the cover removed;

Fig. 3 is a section on the line 3—3, Fig. 2;

Figs. 4, 5 and 6 are views in perspective of elements of the device normally occupying positions within the tank as illustrated in Figs. 2 and 3 and removable from the tank for cleansing; 10

Fig. 7 is a view in perspective of one of the elements of the members shown in Fig. 5, and 15

Figs. 8 and 9 are, respectively, diagrammatic and detached perspective views illustrating the operation of the device.

With reference to Figs. 1 to 3 of the drawings, apparatus made in accordance with my invention comprises a tank consisting primarily of a base or body portion 1 and a lid or cover 2, the latter being removable. At one end, as shown at the right of Figs. 2 and 3, the body 1 is provided with an intake spout 3 the lower end of which adjoins the bottom of the tank and which extends upwardly at an angle away from the end wall 4. This same end of the tank is provided with an overflow duct 5 the inner end of which communicates with the bottom of an overflow chamber 6 in the interior of the tank and which extends downwardly at an angle from the end wall as illustrated. A third and normally closed duct 7 extends from the bottom of the end wall 4 and serves as a discharge port from which the liquid contents of the tank may be readily removed, the position of this duct 7 being indicated in broken lines in Fig. 3. 20

In the interior of the tank and at the opposite end is a curved baffle 8 which terminates at its inner and lower end in a vertical section 9 and whose outer and upper end lies flush with the bottom of a slotted port 11, which as shown in Fig. 1 extends across substantially the entire width of the tank; and the adjoining end wall of the body 45 1 is provided with a slide 12 which may be elevated through the medium of a lip 13 from the normal depressed position in which it is shown in Fig. 3 to cover the port 11, this slide also having the function of a clamp, as hereinafter more fully 50 described. It will be noted that the corresponding end wall 14 of the cover 2 is so formed as to leave the slot 11 exposed when the cover is in place, as shown in Fig. 1. With the exception of two ribs 15 in the form in the present instance of 55

rods secured in vertical position to the opposite side walls of the body 1 of the tank adjacent the lower end of the baffle 8, the aforescribed elements constitute the fixed or permanently attached portions of the tank proper.

Adapted to fit within the body 1 of the tank in a position overlying the baffle 8 is a member 16 shown in perspective in Fig. 4. This member comprises side walls 17 which in assembly and as shown in Fig. 2 lie contiguous to the side walls of the tank body 1, these walls being connected by a continuous web 18 shaped as best shown in Fig. 3 to conform at the bottom with the curved baffle 8 upon which it normally rests. The upper surface of the web 18 forms a smooth curve terminating at one end at or adjacent to the port 11; while the inner portion of the web is shaped to provide a cavity 19 which in assembly is occupied by a film roll holder 21 shown in perspective in Fig. 5 and hereinafter described in detail. The member 16 also comprises a curved web 22 which extends as shown in Figs. 2 and 4 between the side walls 17, this web lying in spaced relation to the upper portion of the web 18 and being so arranged that its outer edge in assembly registers with the upper edge of the slot 11, as shown in Fig. 3. The inner ends of the walls 17 are provided on the inner surfaces with ribs 23, which in effect define the inner vertical edges of the walls and function as hereinafter described to locate and partially support the film roll holder 21. The member 16 also comprises a transverse rod 24 which is supported in and extends between the side walls 17, this rod as hereinafter described functioning as a guide for the film fed into the tank from the film roll supported in the holder 21.

The holder 21, as shown in Figs. 2, 3 and 5, consists of a plate 25 the lower reduced portion of which is bent into the form of a bead or curved apron 26. The plate 25 supports a fixed bracket 27 provided with an inwardly projecting pin 28 which constitutes a journal for one end of the film spool. The opposite end of the film spool is journaled on a similar pin shown projecting from an oppositely arranged bracket 29, see Fig. 7, which is slidably mounted on the plate 25 for adjustment to and from the bracket 28. In the present instance, the base portion 31 of the bracket 29 is extended and is provided with a slot 32, the base portion 31 being confined against the side of the plate 25 by means of a retaining plate 33 secured in spaced relation to the plate 25 by means of rivets or other suitable elements 34 which extend through the slot 32 of the bracket 29 whereby the said bracket is supported for its rectilinear adjustment movement. The holder 21 also comprises a leaf spring 35 which is secured to the base plate 25 and extends inwardly between the spool-supporting brackets 27 and 29 and which as shown in Fig. 8 is adapted to exert pressure against the side of the film roll 36. In assembly, the side edges of the plate 25 are slidably supported between the ribs 23 of the member 16 and the ribs 15 of the tank body, and a transverse rib 37 on the plate 25 rests in assembly and as shown in Fig. 3 upon the upper ends of the ribs 15 whereby the holder 21 is positioned properly within the tank body. It will be noted that both the member 16 and the holder 21 may readily be removed from the tank body when required.

The device further comprises a skeleton frame or rack 38 shown in perspective in Fig. 6. This

of suitable gauge, comprises longitudinal base elements or rods 39, 39, the terminal ends 41 of which are turned down to form feet, which in assembly and as shown in Fig. 3 rest upon the bottom of the tank body 1 and support the frame 38 in an elevated position in the bottom of the tank. The rods 39 are connected by transverse rods 42 and 43. The rack 38 further comprises upper longitudinal rods 44, 44 which over their greater length extend above and in parallel alignment with the lower rods 39. At one end of the frame the rods 44 are offset outwardly, as indicated at 45, and these offset terminal ends are provided with bearings 46 in which is journaled a reel 47. This reel in the present instance comprises heads 48 in the form of disks having trunnions 49 which are journaled in the bearings 46, and an annular series of rods 51 extends between the disks 48 to form the working body of the reel. The upper rods 44 of the frame are connected by means of transverse rods 52, 52, which also function as a support for the film, as herein-after described.

Extending upwardly above the upper rods 44 and adjacent the opposite ends of the rack are loops 53, 53 which in assembly and as shown in Fig. 3 extend substantially to the top of the body 1 of the tank and which provide readily available means for inserting and withdrawing the rack from the tank. That one of the loops 53 which adjoins the end of the rack in which the reel 47 is mounted also forms a support for the upper ends of two curved rods 54, 54, these rods extending downwardly between the offset ends 45 of the upper longitudinal rods 44 and being suitably secured at their lower ends to the inner sides of the lower longitudinal rods 39, as best shown in Fig. 3. The rods 54 form a support for an apron or guard plate 55 which embraces the outer side of the reel 47.

As shown in Fig. 2, the rack 38 is adapted to rest in the bottom of the tank and extends from the right-hand end of the tank, as viewed in the said drawings, to a point adjoining the inner end of the baffle 8 and of the member 16. The upper longitudinal rods 44 of the rack occupy a plane somewhat above the lower inner ends of the member 16, and the adjoining ends of these longitudinal rods are curved down, as indicated at 56 in Fig. 3, to a point adjoining the inner lower end of the continuous web 18. It will be apparent that when the tank is filled with liquid to a point determined by the position of the overflow chamber 6, the entire rack, with the exception of the upper ends of the loops 53, will be immersed. The normal position of the rack transversely of the tank is determined by the offset ends 45 of the rods 44 and by a rod 50 at the other end of the rack which projects at both ends into proximity to the side walls of the tank, see Figs. 2 and 6.

In the use of the apparatus for developing photographic films the procedure is as follows: As illustrated in Fig. 9, the backing strip 57 of the film roll is unwound from the spool to an extent exposing the free end of the gummed paper leader 58a conventionally provided for the film strip 58. To this free end is attached, preferably by means of the said adhesive, a guide strip 59. This can be done under daylight conditions without danger of adversely affecting the picture-containing portions of the film, since these portions remain covered by the backing paper. With the film spool inserted in the holder 21 as

previously described and as illustrated in Fig. 2, and with the spring 35 engaging the film roll and preventing the film from loosening on the spool, the free end of the backing paper 57 is passed 5 over the top of the web 18 and through the port 11. The guide strip 59 is passed downwardly under the rod 24 and bead 26, longitudinally over the transverse bars 52 at the top of the rack 38, around the reel 47, and back under the transverse bars 52 to the opposite end of the rack. At this point, it is passed between the baffle 8 and the web 18 of the member 16 to and through the port 11. The cover 2 of the tank may now be placed in position to exclude all light from the 15 interior of the tank. Entrance of light into the tank through the port 11 is effectively excluded by the webs 18 and 22 of the member 16 in conjunction with the curved baffle 8. As regards the ducts 3, 5 and 7, it is proposed to employ on each 20 of these ducts short sections of rubber tubing which form effective traps preventing entrance of light to the interior of the tank through these openings, although obviously the ducts could be formed to provide in themselves effective light traps. The free ends of the backing paper 57 and the guide strip 59 which project from the 25 port 11 are pulled away from the end of the tank, with the result that the film is unwound from its spool and drawn into a looped position 30 on the rack 38 and around the reel 47. This operation by reason of the proximity of the two strips can be conducted with one hand, the strips being withdrawn simultaneously. During this 35 operation, both the film and the backing strips are maintained under tension, and there is no possibility for the strips to buckle and jam. When the film has been entirely unwound from the spool, the slide 12 may be elevated to close the port 11 and also to clamp the backing paper and 40 the guide strip tightly in position, thereby giving assurance that the film is held fixed in its position upon the rack 38. Preferably the parts are so proportioned that when the film strip is entirely transferred from the spool to the rack, 45 the paper leader 58a will lie between the baffle 8 and web 18, while the guide strip 59 is entirely withdrawn from the tank.

Sufficient developer solution is passed into the tank through the duct 3 to entirely cover the film supported as previously described upon the 50 rack. This may be a measured quantity of the solution or the solution may be passed into the tank until the latter is full, as indicated by flow of solution through the overflow duct 7. In either 55 case, the overflow provides a free passage of air from the tank as the solution is admitted, thereby preventing trapping of air and formation of air bells interfering with the normal developing operation. When the film has been thus immersed 60 in the solution a sufficient length of time to complete the developing operation, the developer solution may be withdrawn from the tank through the discharge duct 7 and may be collected for further use in subsequent developing operations. 65 Water is then flowed through the intake 3 and may be continuously circulated through the tank, from which it passes through the overflow until the film is completely free from traces of the developer solution, after which the cleansing 70 water may be removed from the tank through the discharge duct 7, and may be replaced in obvious manner by a fixing solution, which with the exception of the final washing completes the developing process.

75 During this entire process, the film has been

maintained in complete darkness, so that the apparatus is adapted for daylight development of the panchromatic and supersensitive films now in common use. The apparatus, however, by simple removal of the cover, provides for inspection of the film at any time during the developing process by elevating the rack. It will be noted that the apparatus provides for the practical exclusion of the backing paper and the guide and leader strips from active contact with the liquid-treating mediums. The backing strip in particular is maintained at all times out of contact with the solutions, this being important by reason of the fact that frequently contact of the backing paper with the developer solution results in a staining of the solution and resultant damage to the film. The guide strip also is effectively excluded from contact with the solutions, in that the latter is removed from the space between the baffle 8 and the web 18 in which the inner end of the strip may lie. Where the length of the film is such that a portion of the guide strip remains in the tank proper, a material may be used for the strip which is inert to the developing chemicals, so that there is no danger of damage to the film from this source.

As previously set forth, a desirable feature of the apparatus resides in the fact that the film during the developing process is maintained in a definite fixed position within the tank in which all parts thereof are uniformly exposed to the developing chemicals. In this position, no part of the film can come in contact with another part. By making the film spool holder 21 adjustable, the device is adapted for different sizes of film. The construction is simple and relatively inexpensive and provides for the removal of all of the working parts for thorough cleaning after use. So far as I am aware, the apparatus is the first that provides for the complete processing of a photographic film including treatment of the film with both the developing medium and the fixing medium and the intermediate and subsequent washing operations by a continuous process and without recourse to a dark room or the equivalent.

I claim:

1. In photographic developing apparatus for roll films, the combination with a light-proof tank having a detachable cover, of a rack separate from the tank and from said cover adapted to support the film strip in substantially horizontal position in the bottom of the tank and removable from the latter, means providing for transfer within the tank of the film strip from the roll to the rack and for simultaneous separation from said film of its backing strip, and means operative while the tank is substantially in normal position for admitting and discharging liquids to and from the tank while the said cover is in position.

2. In photographic developing apparatus for roll films, the combination with a light-proof tank having a detachable cover, of a support for said roll mounted in the upper part of said tank, a rack adapted to support the film strip in substantially fixed position in the bottom of said tank, means providing for transfer within the tank of the film strip from the roll to the rack and for simultaneous separation from said film of its backing strip, means for admitting a liquid to the tank and for discharging said liquid while the cover is in position, and overflow means adapted to limit the height of the liquid within the tank to a level below the top of said roll.

3. In photographic developing apparatus for roll films, the combination with a light-proof tank having a detachable cover, of means for supporting said roll in the upper part of said tank, a rack adapted to support the film strip in substantially fixed position in the bottom of the tank, means providing for transfer within the tank of the film strip from the roll to the rack, means for admitting a liquid to the tank and for discharging said liquid while the cover is in position, overflow means for limiting the height of the liquid in the tank to a level below the top of said roll, and means operative simultaneously with said transfer means for separating the backing strip from said film and for segregating said backing strip from the portion of said tank below said overflow.

4. In photographic developing apparatus for roll films, the combination with a light-proof tank comprising a detachable cover, of a horizontal rack for the film strip located in the bottom and at one end of said tank, a film roll support mounted in the upper portion and at the opposite end of said tank, a slot in the wall of said tank at the end thereof occupied by said roll support, and removable means positioned at the slotted end of said tank for providing light-excluding channels extending from said slot to the roll film support and to the adjoining end of said rack respectively.

5. In photographic developing apparatus for roll films, the combination with a light-proof tank comprising a detachable cover, of a horizontal rack for the film strip located in the bottom and at one end of said tank, a film roll support mounted in the upper portion and at the opposite end of said tank, a slot in the wall of said tank at the end thereof occupied by said roll support, a wall providing an elongated surface extending from the slot to the adjoining end of the rack, and a removable element having a lower surface conforming to and normally resting upon said elongated surface and having an extended upper surface forming a guide extending from said slot toward the roll support.

6. In photographic developing apparatus for roll films, the combination with a light-proof tank comprising a detachable cover and having a transverse slot adjacent the top of one end wall, means for supporting a film roll in the upper part of the tank adjacent said slotted end wall, a wall element extending downwardly from the slot and toward the opposite end of the tank and providing an extended guide surface terminating in the lower part of the tank, a member having a lower surface conforming to and normally resting upon said guide surface and having an upper surface extending from said slot toward the roll support, and a rack in the bottom of the tank comprising upper and lower film-supporting levels extending from the inner end of said wall element toward the opposite end of the tank and having toward said opposite end means for guiding the film strip from the said upper level to the lower level.

7. In photographic developing apparatus for roll films, the combination with a light-proof tank comprising a detachable cover and having a transverse slot adjacent the top of one end wall, means for supporting a film roll in the upper part of the tank adjacent said slotted end wall, a wall element extending downwardly from the slot and toward the opposite end of the tank and providing an extended guide surface terminating in the lower part of the tank, a member having a lower surface conforming to and normally resting upon said guide surface and having an upper surface extending from said slot toward the roll support, a rack in the bottom of the tank comprising upper and lower film-supporting levels extending from the inner end of said wall element toward the opposite end of the tank and having toward said opposite end means for guiding the film strip from the said upper level to the lower level, means for admitting a liquid to the tank and for discharging said liquid while the cover is in position, and overflow means located above the said upper level of the rack and below the top of a roll mounted in said roll support.

8. In photographic developing apparatus for roll films, the combination with a light-proof tank comprising a detachable cover and having a transverse slot adjacent the top of one end wall, means for supporting a film roll in the upper part of the tank adjacent said slotted end wall, a wall element extending downwardly from the slot and toward the opposite end of the tank and providing an extended guide surface terminating in the lower part of the tank, a member having a lower surface conforming to and normally resting upon said guide surface and having an upper surface extending from said slot toward the roll support, and a rack in the bottom of the tank comprising upper and lower film-supporting levels extending from the inner end of said wall element toward the opposite end of the tank and having toward said opposite end means for guiding the film strip from the said upper level to the lower level, the rack, the roll holder and said member being removable from the tank whereby all surfaces of the apparatus are readily available for cleaning.

9. In photographic developing apparatus for roll films, the combination with a light-proof tank having a detachable cover, of a support for said roll mounted in the upper part of said tank, a rack adapted to support the film strip in substantially fixed position in the bottom of said tank, means providing for transfer within the tank of the film strip from the roll to the rack and for simultaneous separation from said film of its backing strip, means for admitting a liquid to the bottom of the tank and for discharging said liquid while the cover is in position, and means providing for free escape of air from the upper portion of said tank as the liquid is admitted.

HAROLD A. WINDISCH.
